COMBINED REAR LIGHT, STOP LIGHT, BACK-UP LIGHT, AND FENDER TRIM FOR AUTOMOTIVE VEHICLES

Walter A. Wengren, Birmingham, Mich., assignor
to Packard Motor Car Company, Detroit, Mich.,
a corporation of Michigan

Application August 10, 1953, Serial No. 26,389

Term of patent 14 years

(Cl. D48—32)

To all whom it may concern:

Be it known that I, Walter A. Wengren, have invented a new, original, and ornamental Design for Combined Rear Light, Stop Light, Back-Up Light, and Fender Trim for Automotive Vehicles, of which the following is a specification, reference being had to the accompanying drawing, forming a part hereof.

Figure 1 is a side view of the combined rear light, stop light, back-up light, and fender trim for automotive vehicles, showing my new design.

Figure 2 is a rear elevation of the design shown in Figure 1.

Figure 3 is a rear perspective of the design shown in Figure 1; and

Figure 4 is a top plan view of the design shown in Figure 1.

The fragmentary portion of the rear fender disclosed by means of dotted lines in Figs. 3 and 4 are shown only for purposes of illustration.

I claim:

The ornamental design for a combined rear light, stop light, back-up light and fender trim for automotive vehicles, as shown and described.
